INVENTOR.
EDWIN ANDERSON.
BY Chas. C. Townsend

ATTORNEY.

UNITED STATES PATENT OFFICE.

EDWIN ANDERSON, OF SAN FRANCISCO, CALIFORNIA, ASSIGNOR, BY MESNE ASSIGNMENTS, TO STAR CAN OPENER COMPANY, OF SAN FRANCISCO, CALIFORNIA, A CORPORATION OF CALIFORNIA.

CAN OPENER.

Application filed June 8, 1921. Serial No. 476,066.

To all whom it may concern:

Be it known that I, EDWIN ANDERSON, a citizen of the United States, residing at the city and county of San Francisco and State 5 of California, have invented new and useful Improvements in Can Openers, of which the following is a specification.

This invention relates to a can opener. It is a principal object of the present invention 10 to provide a can opener which may be directly and positively applied to the end of a can and thereafter actuated to accurately and positively cut through the wall of the can immediately below the double seam, all 15 of which operation may be brought about without mutilation of the can body or without spilling the contents thereof.

The present invention contemplates the use of a guide roller cooperating with a cutting roller, said pair of rollers being movable relative to each other and adapted to cut through the body of the can while automatically moving around the circumference 25 of the can.

The invention is illustrated by way of example in the accompanying drawing, in which—

Fig. 1 is a view in side elevation showing the complete invention as applied to a can a 30 part of which is broken away;

Fig. 2 is a view in plan showing the can opener operatively disposed relative to a can;

Fig. 3 is another form of the present invention by which the same result may be obtained.

Referring more particularly to the drawing, 10 indicates a can having a cap 11 disposed thereover and bound thereto by a suitable double seam 12. In this class of cans the main portion of the cap is depressed, thus forming an outwardly extending rib at the end of the can. Acting against the inner face of this rib which in reality constitutes the double seam, is a guide roller 13. This guide roller has a flat end face resting against the flat end of the can cap and a circumferential face resting against the inner side of the rib or seam. The roller is free 45 to rotate upon a pin 14 carried on the lower face of a jaw member 15. The jaw member

is formed as a continuation of a handle 16. A pivot bolt 17 is carried by the handle and pivotally connects it with a second handle 18 having a jaw 19. The jaw 19 is formed with a boss 20 through which a crank shaft 21 extends. Secured to the lower end of this shaft and against the under flat face of the jaw 19 is a combined forward and cutting member 22. This member comprises a cylindrical feed roll 23 and a circular cutting disk 24. The outer circumference of the feed roll is knurled to frictionally engage the face of the double seam 12. The cutting disk 24 is formed with a bevelled cutting edge having a square upper face and a bevelled lower face. The thicknesses of the disks 13 and 23 of the rollers are such as to cause the cutting edge of the disk 24 to penetrate the side of the can along a line beneath the inner face of the can cap 11, as clearly shown in Fig. 1. Thus, when the cutting disk is rotated by the crank arm 25 the can cap will be severed from the can at a point below the double seam, thus leaving 75 a smooth undistorted lip around the body of the can.

When the can is being rotated between the rollers the cutter edge being of greater diameter than the rollers is caused to advance 80 through the can material while its roller merely rolls against the can edge, thereby causing a cleaner cut than if its action was that of rolling through the said material.

In the form of the invention shown in Fig. 85 3 the roller 13 is mounted upon a pivot pin 14 carried at the end of a rigid bar 15. The element 22 is slidably mounted on the bar 15 and is carried by a slide block 26 through which the crank shaft 21 extends. A thumb 90 piece 27 is formed at the end of this block so that the cutting disk 24 may be forced outwardly to penetrate the side wall of the can. In the operation of the present invention the handles 16 and 18 are separated, thus causing the rollers 13 and 23 to move apart. The roller 13 is then positioned within the recessed portion of the can cap 11 and held against the inner face of the seam. The plier handles are then forced together as 95 100 they are gripped by one hand of the operator and will tend to cause the sharp cutting

edge of the cutting disk 24 to penetrate the side wall of the can. This action will continue until the circumferential face of the feed roller 23 has positively engaged the can, 5 after which the handles are held in position while the crank 25 is rotated. The force exerted upon the handles will cause frictional engagement of the feed roller 23 with the seam and will produce an advance movement 10 of the cutting element as the feed roller is continuously rotated. The seam of the can will be positively gripped between the guide roller 13 and feed roller 23, while the upper flat face of the cutting disk 24 will tend to 15 hold the disk in position to cleanly cut the can at a point directly below the double seam.

In the form of the invention shown in Fig. 3 the same result is accomplished, al- 20 though the cutting element 22 is bodily moved by the slide block 26 and is held in position by outward pressure against the thumb piece 27.

It will thus be seen that the device here 25 disclosed is capable of universal application to double seamed cans and, while positively holding the can will permit the cap to be cleanly and readily severed from the can body.

30 While I have shown the preferred form of my invention, it is to be understood that various changes may be made in the device by those skilled in the art without departing from the spirit of the invention.

35 Having thus described my invention, what I claim and desire to secure by Letters Patent is:

1. In a can opener, a driving roller fixed on a spindle and having a knurled periphery, a pair of handle members pivoted together one of said members having a recess, the other member carrying a bearing adapted to seat in said recess when the members are gripped together about the pivot, a spindle and hand operating portion carried in said bearing and adapted to rotate said driving roller, and an idler roller on the other member positioned opposite said driving roller, and a cutter disc adjacent one of said 45 rollers and arranged to overlap the handle of the other roller when in cutting position.

2. In a can opener a driving roller and opposite thereto an idler roller, a cutter disc having a common axis with one of said 50 rollers, a pair of handle members pivoted together as levers of the first order, one of said rollers mounted on one end of one of the members and the other roller and the cutter disc mounted on the end of the other 55 member, said cutter disc being directly interposed between the pivot connecting the handle members and the axis of the first-named roller when said members are in cutting position, and means for rotating one of said 60 rollers.

3. In a can opener, a driving roller fixed on a spindle and having a knurled periphery, a pair of handle members pivoted together one of said members having a recess, the other member carrying a bearing adapted to seat in said recess when the members are gripped together about the pivot a spindle and hand operating portion carried in said bearing and adapted to rotate said driving roller, and an idler roller on the other 70 member positioned opposite said driving roller, and a cutter disc adjacent one of said rollers, said cutter disc being directly interposed between the pivot connecting the handle members and the axis of the first-named roller when said members are in cutting 75 position.

4. In a can opener a driving roller and opposite thereto an idler roller, a cutter disc having a common axis with one of said 80 rollers, a pair of handle members pivoted together as levers of the first order, one of said rollers mounted on one end of one of the members and the other roller and the cutter disc mounted on the end of the other member 85 and said cutter disc being directly interposed between the pivot connecting the handle members and the axis of the first-named roller when said members are in cutting 90 position whereby when the handles are gripped together the axes of the two rollers and the cutter disc are brought nearly into alignment with the said pivot.

5. In a can opener, a driving roller fixed on a spindle and having a knurled periphery, a pair of handle members pivoted together one of said members having a recess, the other member carrying a bearing adapted to seat in said recess when the members are gripped together about the pivot a spindle and hand operating portion carried in said bearing and adapted to rotate said driving roller, and an idler roller on the other member positioned opposite said driving roller, and a cutter disc adjacent one of said 100 rollers, said cutter disc being directly interposed between the pivot connecting the handle members and the axis of the first-named roller when said members are in cutting 105 position, whereby when the handles are gripped together the axes of the two rollers and the cutter disc are brought nearly into alignment with the said pivot.

6. In a can opener a driving roller and opposite thereto an idler roller a cutter disc having a common axis with one of said 110 rollers, hand operable gripping members, one of said rollers mounted on one end of one of the members and the other roller and cutter disc mounted on the end of the other member, said cutter disc being interposed 115 between the axis of the first named roller and said gripping members when in cutting position, and means for rotating one of said rollers.

7. In a can opener a driving roller and opposite thereto an idler roller, a cutter disc having a common axis with one of said rollers, hand operable gripping members, one of said rollers mounted on one end of each of said members and said cutter disc being interposed between the axis of the first named roller and the gripping members when said members are in cutting position, whereby, when the handles are gripped together the axes of the two rollers and the cutter disc are brought substantially into a line passing between said gripping members. 10

EDWIN ANDERSON.
